Primary Examiner — Cynthia Ramirez(74) *Attorney, Agent, or Firm* — Schiff Hardin LLP**CLAIM**

The ornamental design of an offset handle for manual hoist, as shown and described.

DESCRIPTION

FIG. 1 is a perspective view taken from the upper right-hand side of an offset handle for manual hoist;
 FIG. 2 is a front elevational view thereof;
 FIG. 3 is a rear elevational view thereof;
 FIG. 4 is a side elevational view of the left side thereof;
 FIG. 5 is a side elevational view of the right side thereof;
 FIG. 6 is a top plan view thereof; and,
 FIG. 7 is a bottom plan view thereof.

In the drawings, the broken line depict portions of the offset handle for manual hoist that form no part of the claimed design.
